ALOIS WEIGEL, OF KINTYRE, NORTH DAKOTA

PLOW LAY ATTACHING DEVICE

Application filed April 10, 1931. Serial No. 529,188.

This invention relates to a plow lay attaching device and it consists in the novel features hereinafter described and claimed.

An object of the invention is to provide a device of the character stated especially adapted to be used upon a turning plow and serving as means for securely holding the lay in proper position with relation to the mold board.

- 10 In plows of this character it is the usual practice to provide a single bolt for holding the lay in proper position with relation to the mold board. After continued use the bolt is liable to become loose and consequently the 15 lay is easily broken because it is not fastened tightly. A further object of the present invention is to provide a device which at all times will tightly draw the lay up close to the mold board so that the lay is tightly held 20 with relation to the mold board should the bolt become loosened.

In the accompanying drawings:—

Figure 1 is a perspective view of a plow with parts broken away showing the attaching device applied to the plow beams and in position with relation to the lay and mold board of the plow when the parts are held tightly together.

Figure 2 is a bottom plan view of the 30 plow.

Figure 3 is a detailed transverse sectional view cut on the line 3—3 of Figure 1.

As illustrated in the accompanying drawings the plow includes the usual beam 1, mold 35 board 2 and lay 3. A cleat 4 is applied to the under side of the mold board and is provided with a slot 5 adapted to receive a bolt 6 carried by the lay 3. When the lay 3 is in proper position with relation to the mold board 2 the bolt 6 has been slipped into the slot 5 and has been tightened whereby the lay is held with relation to the mold board.

The attaching device includes a bracket 45 7 secured to the beam 1 by means of a bolt 8, the said bracket being prevented from turning with relation to the beam by an angularly extending end portion 9 which engages against the edge of the said beam as clearly indicated in the Figures 2 and 3 of

the drawings. The bracket 7 is provided with a stud 10 upon which is pivoted a lever 11, the lever 11 having a curved end portion 12. A link 13 is pivotally connected at one end with the curved end of the lever 12 and is provided at its other end with an angular extension 14 which slidably receives a rod 15. The rod is provided at one end with a flat head 16 having a slot 17 which receives a stud 18 attached to the under side 60 of the lay 3. Nuts 19 and 20 are mounted upon the rod 15 and a coiled spring 21 surrounds the said rod and is interposed between the nut 20 and the angularly disposed end portion 14 of the link 13. 65

When the lever 11 is swung to the position as shown in Figure 1 of the drawings the spring 21 is compressed by the angularly disposed end 14 of the link 13 and inasmuch as the slot 15 of the head 16 receives 70 the stud 18 the lay is drawn up tightly at its upper edge against the lower edge of the mold board 2 and the lay is held in this position should the bolt 6 become loose.

From the foregoing description taken in 75 conjunction with the accompanying drawings it will be seen that simple and durable means are provided for securely holding the lay of a plow in proper position with relation to the mold board thereof, and in the event that the usual securing bolt should become loosened the lay is held in position and is prevented from vibrating or becoming broken by reason of vibration.

Having described the invention what is 80 claimed is:—

1. A plow lay attaching device comprising a bracket member for attachment to the plow, a lever pivoted upon said bracket member and having a curved end portion, a link pivoted to the curved end portion of the lever, a rod slidably in the link, and a spring interposed between a fixed point upon the rod and a fixed part of the link, said 85 rod having a slotted head adapted to receive a part carried by the lay.

2. A plow lay attaching device comprising a bracket member, a lever pivoted to the bracket member and having a curved end portion, a link pivoted to the curved end por- 90 95 100

tion of the lever and having an angularly disposed end portion, a rod slidably mounted in the angularly disposed end portion of the link, a spring interposed between the angularly disposed end portion of the link and a fixed point upon the rod, said rod having a slotted head, and a lug carried by the lay and adapted to enter the slot of said head.

3. A plow lay attaching device comprising a bracket member having a lug adapted to engage the edge of a plow beam and provided with a pivot stud, a lever having a curved end portion pivoted upon the said stud, a link pivoted to the curved end portion of the lever and having an angularly disposed end portion, a rod slidably mounted in the angularly disposed end portion of the link, a spring interposed between the angularly disposed end portion of the link and a fixed point of the rod, said rod having a head portion provided with a slot and the lay having a lug adapted to enter said slot, and a stop member adapted to limit the longitudinal movement of the rod at a point between said head and the angularly disposed end portion of the link.

In testimony whereof I affix my signature
ALOIS WEIGEL.
